Specification for Design.

Patented Apr. 25, 1916.

Application filed January 13, 1915. Serial No. 2,084. Term of patent 7 years.

To all whom it may concern:

Be it known that I, RALPH E. BEERS, a citizen of the United States, residing at Trenton, in the county of Mercer and State of New Jersey, and whose post-office address is 99 Hillcrest avenue, Trenton, New Jersey, have invented a new, original, and ornamental Design for Crate-Heads, of which the following is a specification, reference being had to the accompanying drawing, forming part thereof.

The figure is an end elevation of the crate head, showing my new design.

I claim:

The ornamental design for a crate head, as shown.

In testimony whereof I affix my signature in the presence of two witnesses.

RALPH E. BEERS.
